UNITED STATES PATENT OFFICE.

FRANCIS S. INCO, OF LOS ANGELES, CALIFORNIA.

PORTABLE CLOSET BED.

Application filed February 26, 1923. Serial No. 621,451.

My invention relates to foldable beds which are adapted to be concealed in a suitable closet or compartment when not in use.

It is an object of the invention to provide a bed of this character having a very narrow carriage and an extensible means mounted upon the carriage for preventing the bed from overturning when being lowered from the raised position into horizontal position.

The especial advantages and further objects will be made evident hereinafter.

Referring to the drawings which are for illustrative purposes only,

Fig. 1 is a side elevational view of a closet bed incorporating the features of my invention.

Fig. 2 is a view taken as indicated by the line 2—2 of Fig. 1.

Fig. 3 is an enlarged fragmentary view illustrating the mechanism of the extensible balancing member, in which view the member is shown in raised position.

Fig. 4 is an enlarged fragmentary section showing a form of retaining member I have devised.

Fig. 5 is a fragmentary view similar to Fig. 4 showing the manner in which the retaining member rotates inwardly when the spring structure is deflected downwardly.

Fig. 6 is a diagrammatic plan view of an alternative form of spring structure which may be employed with the bed.

Fig. 7 is an enlarged fragmentary plan view of one corner of the spring structure shown in Fig. 6, illustrating the manner in which the retaining edge is formed continuously around the edge of the spring.

Fig. 8 is an enlarged fragmentary section taken upon a plane represented by the line 8—8 of Fig. 7.

The bed structure shown in Figs. 1 to 3 of the drawing comprises a carriage 11 provided with castors 12 which are inserted in the ends of the legs 13 of end frames 14. A pair of these end frames is provided, each of which is provided with a lower cross bar 16 and an upper cross bar 17. An interconnecting bar 18 extends between the lower cross bars 16, serving to join the end frames together to form the carriage 11, and diagonal bars 20 are extended between the cross bars 16 and the interconnecting bars 18 for reinforcing the structure. Vertically from the interconnecting bar 18 are extended a pair of posts 22. These posts are situated

adjacent to the ends of the member 18, and between the upper ends of the posts 22 and the upper cross bar 17 pivot bolts 24 are extended upon which bolts the side bars 25 of the spring supporting structure 26 are pivoted, thus enabling the spring structure 26 to be swung between the raised position shown in full lines and the lowered position shown in dotted lines in that figure.

At the foot of the spring structure 26 a foldable foot frame 27 is secured which may be swung into vertical position as shown at 28 when the spring structure is lowered. Upwardly from the brackets 30 situated at the head of the spring structure 26 there extend posts 31 to which a head board 32 is pivoted at 33. This head board is linked to the carriage structure by links 35 which are turnably secured upon brackets 37 mounted upon the upper cross bars 17. In this manner a parallel link arrangement is provided whereby the head board 32 is maintained in a substantially perpendicular position at all times, with the result that when the spring structure is swung into the raised position, the head board 32 extends substantially perpendicular thereto and serves as a means for clamping the bed clothes and pillows firmly in place while the spring frame is thus raised.

In order to counter-balance the weight of the spring structure, tension springs 40 are employed which are attached to the extreme rearward end of the spring supporting structure and impart a rotative force thereto which assists in swinging the lower end of the spring structure upwardly. It will readily be perceived that such springs also resist the lowering of the spring structure from the vertical position and it is for this reason that the carriages of closet beds have been made of considerable width to prevent their overturning when the lowering of the bed is attempted.

My invention provides a means whereby a very narrow carriage may be employed, and further provides means for stabilizing the structure while the spring member is being lowered, thus preventing the bed from toppling over upon the person attempting to lower it. For this purpose I employ an extensible member 41, which is formed from a light structural angle, and is employed with the legs 42 thereof inwardly directed. At the outer extremity of this U-shaped member 41 short legs 43 are secured which

support castors 44. The inner ends of the legs 42 are pivoted upon rivets 45 located adjacent to the forward ends of the upper cross bar 17, thus making it possible to swing 5 the extensible member 41 from the position in which it is shown in Fig. 1 to the retracted position shown in Fig. 3. The springs 40 which act as a counter-balance for the spring structure 26 are attached to 10 brackets 47 which are swingably mounted upon rivets 48 positioned upon the upper crossbars 17 between the bolts 24 upon which the spring structure is pivoted and the rivets 45 about which the member 41 is swingable. 15 A tension spring 49 extends from the lower end of each bracket 47, in a direction opposite to that of the spring 40, and connects to the member 41 at 50. These springs 49 serve to hold the extensible member 41 either 20 in the retracted position shown in Fig. 3 or the extended position shown in Figs. 1 and 2. It will be seen that as the member 41 is swung outwardly as indicated by the arrow 52, the points 50 at which the springs 49 25 attach thereto will describe an arc around the pivot 45 and the springs upon passing the pivot point will exert their tension in a plane below the pivot point, as indicated by the dotted line 53, thus applying a force 30 which will hold the extensible member 41 securely down and will resist its being raised by hand, or relatively raised due to the tendency for the bed to over-balance as the spring supporting structure 26 is lowered. 35 For the purpose of limiting the downward swing of the extensible member 41, a link 55 is pivoted at 56 to the inner face of each leg 42. In the lower end of each link 55 a slot 58 is formed which rides over a pin 59 40 mounted in a leg 13 of the carriage frame 14. In Fig. 3 the slot 58 is shown raised upon the pin 59 until the upper end thereof comes to rest against the pin, thus preventing further downward travel of the link with the 45 result that a limit to the downward swing of the member 41 is provided. The link 55 is so proportioned that the member 41 will be brought to rest in a position in which the castors 44 will just rest upon the floor as 50 indicated in Fig. 1.

A rivet 60 is placed in each side rail 25 of the spring structure 26 at a point just above that at which the cross portion 61 of the member 41 strikes the side rails, as 55 shown at 62 in Fig. 3. In this manner means are provided for preventing the lowering of the bed structure when the extensible member is in raised position. In order to lower the spring supporting structure 26, the extensible member must first be lowered into the position shown in Fig. 3.

I claim as my invention:

1. In a portable bed, the combination of: a pair of end frames; a lower cross bar on each of said frames; an upper cross bar on

each of said frames; an interconnecting bar extending between said lower bars; a post extending upwardly from said interconnecting bar near each end thereof; a pivot pin extending between the upper end of each post and the upper cross bar adjacent thereto; a bed structure pivoted on said pivot pins; and a stabilizing member secured to said upper cross bars, said stabilizing member being arranged to be extended from retracted position to an extended position prior to the lowering of said bed structure for stabilizing the carriage portion of said bed. 70

2. In a portable bed, the combination of: a carriage structure; a bed structure pivoted to said carriage structure; a yielding stabilizing member pivoted to said carriage independently of said bed structure and adapted to engage the floor when in extended position; said stabilizing member being arranged to swing upwardly from the floor in a plane parallel to the swinging of said bed structure, to a position of engagement with said bed structure; and means for limiting the extended position of said stabilizing member, said means comprising a link pivoted to said stabilizing member having a slot, and a limiting pin secured to said carriage and projecting into said slot. 80

3. In a portable bed, the combination of: a carriage structure; a bed structure pivoted to said carriage structure and having upper and lower positions thereon; a stabilizing member pivoted to said carriage structure and having upper and lower positions thereon; an arm pivoted on said carriage structure; means connecting said arm to said stabilizing member; and yieldable means connecting said arm with said bed structure and tending to hold said bed structure in upper position, the swinging of said bed structure into lower position tending to retain said stabilizing member in its lower position. 100

4. In a portable bed, the combination of: a carriage; a bed pivoted to said carriage and having upper and lower positions thereon; a stabilizing member pivoted to said carriage and having upper and lower positions thereon; and resilient means connecting said bed and said stabilizing member and tending to retain said bed in its upper position and to retain said stabilizing member in its upper or lower position while said bed is in 110 its upper position, said resilient means tending to exert an increased force, holding said member in lower position when said bed is also in its lower position. 115

5. In a portable bed, the combination of: a carriage structure; a bed structure pivoted to said carriage structure; a yielding stabilizing member pivoted to said carriage independently of said bed structure and adapted to engage the floor when in ex- 125 130

tended position, said stabilizing member being arranged to swing upwardly from the floor in a plane parallel to the swinging of said bed structure, to a position of engagement with said bed structure; and means for limiting the extended position of said stabilizing member, said means comprising a link

pivoted to said stabilizing member and having a slot, and a limiting pin secured to said carriage and projecting into said slot. ¹⁰

In testimony whereof, I have hereunto set my hand at Los Angeles, California, this 19th day of February, 1922.

FRANCIS S. INCO.
